UNITED STATES PATENT OFFICE.

FRANK PARIZEK, OF CHICAGO, ILLINOIS.

CAP FOR GASOLINE OR SIMILAR RECEPTACLES.

1,426,501.

Specification of Letters Patent. Patented Aug. 22, 1922.

Application filed March 24, 1921. Serial No. 454,993.

To all whom it may concern:

Be it known that FRANK PARIZEK, a citizen of the United States, residing at Chicago, in the county of Cook and State of

5 Illinois, have invented a certain new and useful Improvement in Caps for Gasoline or Similar Receptacles, of which the following is a full, clear, concise, and exact description, reference being had to the accompanying drawings, forming a part of

10 this specification.

This invention relates to caps for liquid storage receptacles and more particularly to caps for gasoline or similar tanks.

15 It is a purpose of the invention to provide a cap for a tank with a vent so as to permit air to enter the tank upon which the cap is mounted that is so constructed as to prevent leakage of the liquid contained 20 in the tank through the vent due to splashing of the liquid because of movements of the tank, or from any other cause.

It is still a further purpose of the invention to provide a screw cap of the character described above that has screwthreaded engagement with the tank upon which it is mounted and which is provided with circuitous passages to establish communication between the tank and the outer air.

30 The cap is preferably provided with a cross rib on the top thereof that is hollow and which is separated from the hollow body portion of the cap by a partition provided with openings communicating with the space in the body portion and the hollow 35 of the rib, and provided with an opening in a wall of the rib communicating with the outside air and with the space within the rib.

40 It is also an object of the invention to provide a cap of the character described above with passages connecting the space within the rib with the space within the cap that extend at an oblique angle to the vertical so that any liquid that may be splashed into the chamber in the rib will readily flow down the walls of said passages into the receptacle to which the cap is attached.

45 Other objects and advantages of the invention will appear as the description of the accompanying drawings showing one form that the invention may take proceeds. However, I desire to have it distinctly understood that I do not intend to limit myself to the exact details shown and described but that I intend to include as part

of my invention all such obvious changes and modifications of parts as would occur to a person skilled in this art and as would fall within the scope of the claims.

In the drawings:

Fig. 1 is a plan view of the improved cap;

Fig. 2 is a vertical section thereof; and 65

Fig. 3 is a side elevation of a slightly modified form.

Referring in detail to the drawings the improved cap comprises a cylindrical body portion 4 which is shown as being internally screwthreaded at 5 but which may be screwthreaded either externally or

internally, as is common with caps of this character, depending upon the manner in which the receptacle upon which the cap is used is threaded, the cap being shown as being externally screwthreaded at 5' in

Fig. 3. The said cap is provided with a closed end portion 6 as is customary and is provided with a transverse rib 7, which rib is provided so as to enable the cap to be readily screwed into position and unscrewed. The present invention has for its

purpose to provide a cap of the general character outlined that is provided with vent openings so as to permit air to enter the tank and break any vacuum that might occur therein due to emptying of the same and thus permit the flow of liquid from the same to continue without interruption 90

due to this cause. Caps have been ordinarily provided with vent holes that merely extended through the closed end of the cap and through which the liquid in the tank quite often leaked upon agitation 95

of the liquid in the tank from any cause, such as for instance, in the case where the tank is mounted on a vehicle, the agitation of the liquid due to movement of the vehicle. In order to avoid this objection to 100

the vent openings in a cap the particular construction of cap used in the present device has been developed. In the present device the rib 7 is provided with a space 8 within the same and this space is separated from the space within the cylindrical portion of the cap by means of a partition

9, the partition 9 being formed in part integral with the body portion of the cap 4, and the opening remaining in the same being closed by means of the plate 10, it being necessary to make the device in this manner as the casting could not be made with a complete partition between the rib

105

110

and the body portion of the cap without providing an opening somewhere in the rib or cap to permit the removal of the core used in making the mould for the casting. 5. It is preferred to leave this opening in the partition and close it with the plate 10 as this would leave the external surfaces of the cap and rib a smooth casting with no breaks therein. The edges of the partition 10 adjacent the opening therein are provided with offset portions 14, and the edges of the plate 10 are forced into engagement therewith so as to assume a shape corresponding thereto, to firmly hold said plate 15 10 in place. It will be noted that the partition 9 is arched so as to follow substantially the same curvature as the outer surface of the cap so that any liquid that might collect in the chamber 8 will flow 20 down the curved surface of the partition to the outer lowermost edge portions thereof. The partition 9 between the rib and body portion of the cap is provided with a plurality of passages 11 which preferably 25 extend at an oblique angle to the axis of the cap, and the upper wall of the rib 7 is provided with a passage 12 leading to the outer air.

The passages 11 are placed at an oblique 30 angle as shown in Fig. 2 so that if any liquid is splashed up into the same it will readily run down the lower oblique wall of the passage into the tank and will thus aid in preventing clogging of the openings by means 35 of drops of the liquid. The openings 11 are located adjacent the outer edge of the partition so that any liquid in the chamber 8 will flow into the same and down the walls thereof into the receptacle upon which the 40 cap is secured.

It will be seen that in this manner a circuitous passage is provided for the passage 45 of air from the outside of the tank to the interior thereof through the opening 12, space 8, and through the openings 11. Due to this structure the liquid if splashed up against the cap will not pass beyond the space 8 under any circumstances, and will in ordinary circumstances not pass beyond the 50 passages 11, and it will thus be seen that there will be very little possibility that any of the liquid will be splashed out through the opening 12. The cap is provided with a convexed outer surface 13 so as to give the 55 caps a better appearance and the rib 7 is preferably curved at 14 on substantially the same radius as the cap.

Having thus described my invention what I desire to claim and secure by U. S. Letters 60 Patent is:

1. A cap of the character described comprising a cylindrical side wall portion screw-threaded for a portion of its length, and a closed end portion providing a hollow cross 65 rib, said end portion being provided with a

circuitous passage providing a vent for said cap.

2. A cap of the character described comprising a cylindrical side wall portion screw-threaded for a portion of its length, and a closed end portion, said end portion being provided with a double walled portion defining a space between said walls, and passages through both said walls, certain of said passages being inclined to the axis of 75 the cap to allow the liquid to run down the walls thereof, and prevent clogging of said passages by drops of said liquid.

3. A cap of the character described comprising a cylindrical side wall portion screw-threaded for a portion of its length, and a closed end portion, said closed end portion being provided with an external transverse hollow rib, forming a chamber within the end wall of said cap, and said cap being 80 provided with passages extending through one wall of said chamber to the inside of said cap and through another wall of said chamber to the outside of said cap.

4. A cap of the character described comprising a cylindrical side wall portion screw-threaded for a portion of its length, and a closed end portion, said closed end portion being provided with an external transverse hollow rib, forming a chamber within the 95 end wall of said cap, and said cap being provided with passages extending through one wall of said chamber to the inside of said cap and through another wall of said chamber to the outside of said cap, the passages 100 in said walls being out of alignment.

5. A cap of the character described comprising a cylindrical side wall portion screw-threaded for a portion of its length, and a closed end portion, said closed end portion being provided with an external transverse hollow rib, forming a chamber within the end wall of said cap, and said cap being provided with passages extending through one 105 wall of said chamber to the inside of said cap and through another wall of said chamber to the outside of said cap, certain of said passages being inclined to the axis of said cap.

6. A cap of the character described comprising a cylindrical side wall portion screw-threaded for a portion of its length, and a closed end portion, said end portion being provided with a double walled portion defining a space between said walls, one of said 115 walls being arched upwardly, and passages through both said walls, the passages through said arched wall extending obliquely from the lowest part of said arch to drain said space between said walls whereby 120 clogging of said passages by drops of liquid is prevented.

In witness whereof, I hereunto subscribe my name this 10th day of March, A. D., 1921.

FRANK PARIZEK.
